CHAIN SPROCKET FOR A BICYCLE

Keizo Shimano and Norio Sato, both % Shimano Industrial Co., Ltd., 77 3-cho, Oimatsucho, Sakai, Japan

Filed Apr. 11, 1969, Ser. No. 16,684

Term of patent 14 years

Int. Cl. D12—14

U.S. Cl. D90—17

Fig. 1

Fig. 2

FIG. 3

FIGURE 1 is a front view of a chain sprocket for a bicycle embodying our new design;

FIGURE 2 is a side elevation view; and

FIGURE 3 is a centrally vertical cross section view thereof.

We claim:

The ornamental design for a chain sprocket for a bicycle, substantially as shown.
